Inventor:
Joseph Chadwick

United States Patent Office.

JOSEPH CHADWICK, OF WHEATON, ILLINOIS.

Letters Patent No. 69,966, dated October 22, 1867.

IMPROVED WEATHER-STRIP FOR DOORS.

The Schedule referred to in these Letters Patent and making part of the same.

TO ALL WHOM IT MAY CONCERN:

Be it known that I, JOSEPH CHADWICK, of Wheaton, in the county of Du Page, and State of Illinois, have invented a new and useful improvement in Weather-Strips for Doors; and I do hereby declare and make known that the following is a full, clear, and exact description thereof, reference being had to the accompanying drawings, and the letters and figures marked thereon, which form part of this specification.

The object of my invention is to produce a device to be applied at and upon the door and door-sill, whereby the closing of the door operates upon a metallic strip arranged upon the door-sill to raise up one edge of said strip, beneath a rib upon the door, thus forming a sure protection against wind, dust, and storms, excluding the same effectually from the house.

To enable those skilled in the art to understand how to construct and use my invention, I will proceed to describe the same with particularity, making reference, in so doing, to the aforesaid drawings, in which—

Figure 1 represents a front elevation of my invention.

Figure 2 is a transverse section of the same; and

Figure 3 is a plan or top view of the strip and its attachment upon the door-sill.

Similar letters of reference in the several figures denote the same parts of my invention.

D represents the door, E the jambs or casing thereof, and S the door-sill, all of which are constructed and arranged in any of the known forms and modes. A represents a strip of metal or other suitable material, which lies flat upon the door-sill just outside the door, which strip is secured by means of staples b b passing through holes a a in the strip, near its outer edge, and being driven into the door-sill, as shown. By this arrangement the strip is permitted to be raised up from the inner side, as hereinafter described, so as to lie under a ledge, C, upon the door, as seen in fig. 2, and thus thoroughly exclude the rain, dust, wind, and storm from the house, which otherwise would enter through the space under the door. Upon the door is arranged a ledge, C, which is kept in a sloping position by means of a triangular-shaped bar, c, having between it and the door a rubber or other suitable elastic strip, marked d, as clearly shown in fig. 2, the whole being firmly secured to the door by means of screws s or their equivalent, the said rubber forming a close joint between the ledge C and the door, and so preventing the rain from passing down between the ledge and door, which otherwise would thus admit the rain into the room and enter the holes in the door, in which the screws take hold, thereby causing the wood to decay and the ledge to become loosened and unserviceable, thereby doing away with all the advantages aimed at in the employment of the strip. Upon one end of the strip A is attached, at the end remote from the hinged edge of the door, a curved arm, B, which is secured to the strip by means of a screw, as shown, so that when the door is closed nearly into its place, the edge of the ledge C strikes upon said arm B and raises up the edge of the strip A into place, as desired, and as shown in figs. 1 and 2.

Having described the construction and operation of my invention, I will proceed to specify what I claim and desire to secure by Letters Patent:

I claim the arrangement of a rubber packing, d, between the door and ledge C, substantially in the manner and for the purposes described.

JOSEPH CHADWICK.
